UNITED STATES PATENT OFFICE.

MENNO J. ISEBRANDS. OF BLAIRSBURG, IOWA.

AUXILIARY LOCKING DEVICE FOR VAULT DOORS.

Application filed October 12, 1921. Serial No. 507,306.

To all whom it may concern:

Be it known that I, MENNO J. ISEBRANDS, a citizen of the United States, residing at Blairsburg, in the county of Hamilton and 5 State of Iowa, have invented certain new and useful Improvements in Auxiliary Locking Devices for Vault Doors, of which the following is a specification, reference being had to the accompanying drawings.

10 This invention relates to vault doors, and particularly to the locking device thereof.

The general object is to provide means which, if the lock be tampered with, will drop down into position to hold the bolts 15 projected, and particularly to provide means for this purpose so constructed that if the locking mechanism be injured or destroyed by nitroglycerine or other explosives, or the shank of the operating arm of the lock 20 be sawed or cut off by heat, the bolts will be locked by the locking device from any retraction.

Another object is to provide a very simple means to this end which will act to lock the 25 master bar, whereby all the bolts are operated.

My invention is illustrated in the accompanying drawings, wherein:—

Figure 1 is an elevation of a vault door 30 with the improved locking mechanism thereon, the bolts being shown as projected and the safety device raised;

Figure 2 is a like view to Figure 1, but showing the arm of the handle and the 35 shank of the lock nut, and the safety locking device fallen into place to prevent retraction of the bolts;

Figure 3 is an enlarged sectional view approximately on the line 3—3 of Figure 2;

40 Figure 4 is a vertical sectional view on the line 4—4 of Figure 1;

Figure 5 is a perspective view of a trough-shaped fusible member which acts to hold the auxiliary locking device in inoperative 45 position;

Referring to the drawings, 10 designates the outer plate of a vault door of any suitable construction, and 11 the usual iron frame bolted or screwed to the vault door 50 for holding the locking bolts of the vault door. Four main locking bolts 12 are illustrated disposed in parallel relation and extending in a horizontal plane, these bolts being longitudinally shiftable into projected 55 position, and two pairs of vertical locking bolts are shown, designated 13, which are

adapted to be shifted vertically in order to project the bolts 13 or retract them. The bolts 12 are all connected by a vertically extending master bar 14 which is operatively 60 connected to the bolts 12, and each pair of bolts 13 is connected by a bar 15, in turn connected by a bell crank lever 16 to the adjacent bolts 12. This bell crank lever is pivoted upon the main body of the door, as 65 at 17, under the frame 11. It will thus be obvious that when the bolts 12 are projected the bolts 13 will be projected and when the bolts 12 are retracted the bolts 13 will be retracted. The shifting of the bar 14 and, 70 therefore, the projecting of the bolts 12 is secured by means of the usual handle 18 disposed upon the exterior of the door. This handle on its inner face is formed with an arm 19 and an arm 19^a, the arm 19 having a socket 20 formed at its ends for engagement with the bolt 22 of the permutation lock. The arm 19^a is pivoted at 19^a or otherwise connected to the master bar 14 in such manner that when the handle 18 is 80 turned, the master bar may be moved in the direction of the arrow *a* in Figure 1. A combination or permutation lock 21 of conventional form is mounted upon the door and has a bolt 22 which, when projected, extends into the socket 20. Thus when this bolt is projected the handle 18 cannot be rotated.

The purpose of the invention, as before stated, is to provide means, if the combination lock is blown off or knocked off the door, or if the arm 19 or bolt 22 is cut off by heat, acting automatically to lock against the master bar 14 to prevent any inward movement of this bar so that the bolts will 90 be still held projected, this auxiliary locking device, however, remaining inoperative so long as the lock and the arm 19 are not damaged, so as not to interfere with the ordinary use of the lock. The means which 95 have been devised for this purpose consists of preferably two bars 23 which are respectively tiltably mounted upon one of the bolts 12 above the lock 21 and on one of the bolts 12 below the lock 21; these bars remaining stationary at all times, except when the combination or permutation lock is blown off, or when the arm 19 or bolt 22 is cut by heat. The bars 23 are held raised far enough at their ends which carry the 100 shoulders 25 to allow bolts 12 to move longitudinally when main lock is operating.

These bars 23 are held from falling off the bolts 12 by means of strips 24 extending behind the bolts 12, these strips acting to hold the bars 23 steady so that they will not become displaced. Each of the bars 23 extends beneath the master bar 14 and is formed adjacent its end with a shoulder 25 inward of the master bar. When a bar 23 drops to a horizontal position, as illustrated 10 in Figure 2, this shoulder will engage against the master bar 14 and hold the bar from any inward movement. The extremity of each locking bar 24 extends between the master bar 14 and the door 10 so that 15 the locking bar is thus guided in its downward movement and cannot fall out of position.

For the purpose of normally holding the bars 23 in an inclined position with their 20 shoulders spaced from the inner edge of the bar 14, supporting rods 26 and 28 are pivotally connected to the upper and lower bars 23. The adjacent terminal ends 27 and 29 of the rods 26 and 28 are formed with 25 hooks. A member 30 constructed of any suitable fusible substance, such as fusible metal or the like, has one end fastened at 30° to the frame 11 and its other end at 30° to a circular plate upon the back of the combination 30 or permutation lock. This usual circular plate on the back of the combination or permutation lock covers and holds the interior working elements (not shown) of the combination lock in place, it being obvious 35 that when this circular plate is removed, the interior working parts or elements of the combination lock are free to be removed or adjusted.

When it is desired to detach the circular 40 plate from the back of the casing of the combination lock, the screws or other means holding the plate to the combination lock will be removed and the plate with the fusible member 30 will swing downward upon 45 the bolt 30^a as a pivot.

The fusible member 30 has its lower edge bent upward and outward away from the door, as illustrated more particularly in Figure 5, so as to form a flange and the 50 upper face of this flange has a compound curve to form two crests 30^c and a valley 30^d. The hooks 27 and 29 of the rods 26 and 28 engage this upturned flange of the fusible member 30 so as to support the bars 55 23, as shown in Figure 1, the two crests 30^c preventing any swinging movement of these rods 26 and 28, the hooks of which will lie in the valley 30^d.

It will be obvious now that if the lock be 60 blown off or if the bolt 19 be cut through, or be burned through by means of an acetylene torch or by an electric arc, that the fusible member 30 will either be torn away, cut through, or will fuse under the heat, 65 and in any case it will separate, as illustrated

in Figure 2, and the two halves will drop down, thus permitting the supporting rods 26 and 28 to drop down, whereupon the upper and lower locking bars 23 will drop to a horizontal position with their shoulders engaging behind the arm 14, thereby preventing any retraction of this arm, and thereby locking all the bolts of the door and holding said bolts in locked position. In order to operate the lock and open the door after the 70 safety lock comprising the bars 23 has dropped to its locking position, wires 33 and 34 are provided which are attached to the locking bars 23 each at one end. The opposite end of each wire is attached to a 75 support 35 or 36, as illustrated in the drawings. These wires normally are loose, as shown in Figure 1, but are drawn more or less taut when the locking bars 23 drop to their locking positions. The location of 80 these wires 33 and 34 with reference to their supporting means 35 and 36 and the reference to their location on the bars 23 is to be individual to any particular safe. In other words, the location of the supporting 85 members 35 and 36 and the point of attachment of the wires 33 and 34 to the locking bars 23 is to be varied or changed in each and every installation so that, if possible, the wires 33 and 34 will not be arranged alike in any two safes.

Where a safe door is equipped with a safety lock of the character described, a plan or diagram is made as to the arrangement of the wires 33 and 34, which plan or diagram is, of course, secret and is only to be used in case an attempt is made to open the safe. When an attempt is made by burglars to open the safe and the locking bars 23 drop, it is, of course, impossible to open 100 the safe until the locking bars 23 have been raised. Reference is then had to the diagram which discloses the location of the wires 33 and 34. The wall of the door may then be drilled with small holes adjacent where the 105 wires 33 and 34 are disposed and then a small hook or other like tool may be inserted through these holes in order to engage the flexible wires 33 or 34, which may be pulled through the holes far enough to insure a firm grip thereon. The wires 33 and 34 are then pulled sufficiently to raise the bars 23 to a point where the shoulders 25 will disengage from behind the master bar 14. Then the bar 14 may be actuated by the 110 handle 18 and the locking bolts be shifted to unlocked positions, thereby permitting the door to swing open.

Obviously the various details illustrated 115 may be varied in many ways without departing from the spirit of the invention, and these details will, of course, vary in accordance with variations in the locking mechanism and structure of the door. The safety locking device may be constructed to 120

be applied to vault doors of any ordinary construction.

I claim:—

1. The combination with a vault door, 5 bolts therefor, a handle for operating the bolts, means for locking the handle from operation including a bolt shiftable into or out of engagement with the handle, of auxiliary locking devices, and means supporting 10 the auxiliary locking devices in inoperative position including a fusible member extending across the junction of the bolt and handle and adapted to be separated by injury to the bolt or handle, the member being 15 pivotally supported so that when separated it may swing to a releasing position.
2. The combination with a vault door, 20 bolts therefor, a handle for operating the bolts and means for locking the handle from operation including a bolt shiftable into or out of engagement with the handle, auxiliary locking devices, and means supporting the auxiliary locking devices in an inoperative 25 position including a fusible member extending across the junction of the bolt and handle and pivotally supported at its opposite ends and adapted to be separated by injury to the bolt or handle and when separated swinging to a releasing position.
3. The combination with a vault door, 30 bolts therefor, a handle for operating the bolts and means for locking the handle from operating including a bolt shiftable into or out of engagement with the handle, of auxiliary locking members, rods connected to said 35 members, and means engaging the rods to thereby support the auxiliary locking members in an inoperative position including a fusible member extending across the junction 40 of the bolt and handle and upon which the ends of said rods rest, the fusible member being pivotally supported at its opposite ends, the separation of the fusible member releasing said rods.
4. The combination with a vault door having 45 a plurality of locking bolts and a master bar movable in one direction to project the bolts and in another direction to retract the bolts, of a handle for shifting the door, locking mechanism preventing the shifting of the handle, a plurality of auxiliary locking members mounted upon the door and having shoulders adapted, when the auxiliary locking members are shifted to operative position, to engage behind the master bar and hold it from retraction, a fusible member operatively connected to one end of the locking mechanism at the other end to a part 50 of the door and extending across the junction between the locking mechanism and the handle, and a plurality of supporting rods normally resting upon and detachably engaging said member and each connected to one of the auxiliary locking members and 55 normally supporting them in an inoperative

position, the breakage of the locking mechanism and of the handle causing the breakage of said fusible member and a dropping of said supporting rods and the release of the auxiliary locking members.

5. A vault door of the character described having a plurality of locking bolts, a shiftable master bar operatively connected to said locking bolts to cause their retraction or projection, a handle having an arm upon the 70 inner face of the door operatively connected to said master bar to cause its retraction or projection as the handle is turned, a lock including a projectable bolt adapted when projected to engage said handle to prevent 75 its rotation, auxiliary locking bars operatively mounted upon the inner face of the door and having shoulders which, when the locking bars are in a horizontal position, will engage behind the master bar to prevent its 80 retraction, means for sustaining said auxiliary locking bars in an inclined position comprising supporting rods connected to the locking bars, and a member operatively connected to the frame of the door upon the 85 inner face of the door and extending beyond the lock of the door, said member being adapted to be released by injury to parts of the locking mechanism for the door to thereby cause the auxiliary locking bars to drop 90 to their locking position with the shoulders against the master bar.

6. The combination with a vault door having bolts and means for shifting the bolts into or out of projected position including 100 a master bar projectable in one direction to project the bolts and in another direction to retract the bolts, of a handle on the exterior of the door operatively connected to the master bar to retract or project the bolts, 105 locking devices operatively engaged with said handle to prevent its shifting, auxiliary locking members operatively supported upon the door and having shoulders adapted when the auxiliary locking members are shifted to 110 an operative position to engage behind the master bar and hold it from retraction, a member operatively connected to the frame of the door upon the inner face of the door and extending across the juncture of the operating connection between said locking device and the handle, supporting rods detachably engaging said member and connected to the auxiliary locking members and normally supporting them in inoperative positions, the destruction of said member causing the dropping of said supporting rods and the release of the auxiliary locking members, and means connected to the auxiliary locking members whereby they may be 115 raised to their unlocking position.

7. The combination with a vault door having bolts and means for shifting the bolts into or out of projected position including 120 a master bar projectable in one direction to 125

130 normally supporting them in an inoperative

project the bolts and in another direction to retract the bolts, of a handle on the exterior of the door operatively connected to the master bar to retract or project the bolts, 5 locking devices operatively engaged with said handle to prevent its shifting, auxiliary locking members operatively supported upon the door and having shoulders adapted when the auxiliary locking members are 10 shifted to an operative position to engage behind the master bar and hold it from retraction, a member operatively connected to the frame of the door upon the inner face of the door and extending across the junction 15 of the operating connection between said locking device and the handle, supporting rods detachably engaging said member and connected to the auxiliary locking members and normally supporting them in 20 inoperative positions, the destruction of said member causing the dropping of said supporting rods and the release of the auxiliary locking members, and flexible connections each attached at one end to the door 25 and at the other end to the corresponding auxiliary locking member and affording means whereby the auxiliary locking members may be raised to an inoperative position by drilling through the door adjacent 30 to the flexible connections.

8. The combination with a vault door having bolts and means for shifting the bolts in or out of projected position including a master bar, a handle operatively connected 35 to the master bar to shift it, locking mechanism adapted to operatively engage said handle to prevent its being shifted, a supporting member operatively mounted upon the inner face of the door and extending 40 across the juncture between said locking mechanism and the handle and being disposed closely adjacent thereto whereby any attempt to break said connection between the handle and the locking mechanism will 45 divide said member, an auxiliary locking member mounted upon the door and having

a shoulder adapted when the auxiliary locking member is shifted to operative position to engage behind the master bar and hold it from retraction, and a support operatively 50 engaging said auxiliary locking member and holding it in inoperative position and operatively engaging said supporting member, the breakage of said supporting member causing the dropping of said support and the 55 release of the auxiliary locking member.

9. A vault door of the character described having a plurality of horizontally disposed locking bolts, a vertically extending master bar operatively connected to said locking bolts to cause their retraction or projection as the master bar is shifted, a handle operatively connected to said master bar to cause its projection or retraction as the handle is turned, the handle having an arm upon the inner face of the door, a lock including a bolt adapted when projected to engage said arm to prevent the rotation of the handle, a relatively frail supporting member attached to said lock at one end and at its other 60 end operatively attached to the door and extending across the junction between said bolt and the arm on the handle and closely adjacent thereto whereby if any attempt be made to detach the lock from the handle the 65 supporting member will be divided and swing downward, auxiliary locking bars operatively mounted upon the inner face of the door for swinging movement in a vertical plane, the free ends of the auxiliary 70 locking members being disposed between the ends of the door and the master bar, said locking bars having shoulders which, when the locking bars are in a horizontal position, 75 will engage behind the master bar to prevent its retraction, and means for sustaining said auxiliary locking bars in an inclined position, said means being supported by said relatively frail supporting member.

In testimony whereof I hereunto affix my 80
signature.

MENNO J. ISEBRANDS.
